UNITED STATES PATENT OFFICE.

GEORGE McCARN, OF GOODLAND, INDIANA.

POWER MECHANISM FOR RECIPROCATING PLUNGERS.

SPECIFICATION forming part of Letters Patent No. 367,539, dated August 2, 1887.
Application filed April 20, 1887. Serial No. 236,654. (No model.)

To all whom it may concern:

Be it known that I, GEORGE McCARN, of Goodland, in the county of Newton and State of Indiana, have invented a new and Improved 5 Power Mechanism for Reciprocating Plungers, of which the following is a full, clear, and exact description.

This invention relates to a novel means of imparting a reciprocating motion to a plunger, 10 the construction being applicable for use in connection with a hay or vegetable cutter or a hay-press, or for any other purpose where an intermittent compressive force is required.

Reference is to be had to the accompanying 15 drawings, forming a part of this specification, in which similar figures of reference indicate corresponding parts in both the views.

Figure 1 is a plan view of a construction 20 embodying my invention, the parts being represented as they appear when arranged in connection with a cutting apparatus; and Fig. 2 is a sectional view taken on the broken line *x* of Fig. 1.

In the drawings above referred to 25 represents a drum or disk having one or more bosses or projections, 11, which extend outward from the peripheral face of the disk, three of these bosses being preferably employed. To this drum or disk 10, I connect a sweep, 12. A pitman, 13, which is connected at one end to a plunger, 14, is held against the peripheral face of the drum 10 by circular guides 15, which are concentric with the axis of the drum, the pitman 13 being provided with a pin, 16, 35 which extends from either side of the pitman-head and bears against the guides 15, the pitman resting between said guides.

A spring, 17, is connected to the pitman 13 by means of a link, 18, the arrangement being 40 such that as the sweep is turned in the direction of the arrow shown in connection therewith in Fig. 1 the pitman will be forced to the position in which it is shown in dotted lines in said figure by one of the lugs 11, that are carried by the drum or disk 10, and as 45 such lug passes from engagement with the pitman-head the spring 17 will act to return the pitman to the position in which it is shown in Fig. 1.

50 From the above description it will be seen

that a reciprocating motion may be imparted to a plunger when such plunger is mounted in proper guides, and that the compressive force is brought to bear slowly and evenly upon the plunger, but that immediately upon the completion of the full stroke of the plunger it will be quickly returned by the action of the spring. 55

In the application of my invention illustrated in the drawings I have represented the plunger as being provided with a knife, 2, the cutting-edge of which is arranged to be thrown against the cutting-edge of a knife, 3, that is carried by a casing, 20, within which the plunger is mounted, the arrangement being such that by reciprocating the plunger and bringing the two knife-edges together the movement of the plunger may be utilized for the purpose of cutting hay, roots, or any other product. The throw of the spring is limited by a stop, 19, arranged as shown. 70

In the drawings I have represented the plunger-case and the disk 10 as being mounted upon a bed-plate, A; but the two parts might be mounted upon separate foundations provided the two foundations were rigidly connected. 75

In the ordinary operation of the apparatus described, a horse or other draft animal would be connected to the sweep 12, and it will of course be understood that the parts might be mounted so that the horse in his travels would cross over the pitman, or that the parts might be mounted so that the horse would pass beneath the pitman, in which latter case the disk or drum 10 would necessarily be mounted at the top of a vertical shaft, to the lower end of which shaft the sweep would be connected. 85

Having thus fully described my invention, I claim as new and desire to secure by Letters Patent—

1. The combination, with a plunger, of a pitman connected thereto, a disk or drum carrying stops that are arranged to bear against the pitman-head, guides that are concentric with the axis of the drum or disk, a pin or stop carried by the pitman and arranged to bear against the guides, a means for revolving the drum or disk, a spring, and a link connecting the spring and the pitman, substantially as described. 90

2. The combination, with a plunger, 14, carrying a knife, 2, of a plunger-case, 20, provided with a knife, 3, a pitman, 13, connected to the plunger, a disk or drum, 10, provided with bosses 11, guides 15, through which the pitman-head passes, a pin, 16, carried by the plunger, and arranged to bear against the guides, a sweep, 12, connected to the drum or

disk 10, a spring, 17, and a link, 18, connecting the spring and the pitman, substantially as described.

GEORGE McCARN.
